REVERSIBLE BATHING CAP

Peter Jansen, Kolin-Dellbruck, Germany, assignor to Radium Gummiverke m.b.H., Kolin-Dellbruck, Germany, a corporation of Germany

Filed Dec. 31, 1958, Ser. No. 53,994

Term of patent 14 years

(Cl. D3—13)

T 1-1

T 1-2

T 1-3

Fig. 1 is a side elevational view of a reversible bathing cap showing my new design;

Fig. 2 is a front elevational view thereof;

Fig. 3 is a rear elevational view;

Fig. 4 is an enlarged detail of a portion of the material shown on the outer surface of the cap in Figs. 1, 2 and 3;

Fig. 5 is a front elevational view of the cap as it appears in reversed position;

Fig. 6 is an enlarged detail of a portion of the material shown on the outer surface of the cap in Fig. 5; and

Fig. 7 is a section on the line 7—7 of Fig. 6.

I claim:

The ornamental design for a reversible bathing cap, as shown.
